UNITED STATES PATENT OFFICE

168,777

ELECTRIC LAMP

David Borowitz, Chicago, Ill.

Application June 4, 1952, Serial No. 20,037

Term of patent 3½ years

(Cl. D48—20)

To all whom it may concern:

Be it known that I, David Borowitz, a citizen of the United States, and a resident of Chicago, Illinois, have invented a new, original, and ornamental Design for an Electric Lamp, of which the following is a specification, reference being had to the accompanying drawing, forming a part thereof.

Figure 1 is a front elevational view of an electric lamp, embodying my new design;

Figure 2 is a right hand side elevational view thereof;

Figure 3 is a left hand elevational view thereof;

Figure 4 is a top plan view thereof; and

Figure 5 is a rear elevational view thereof.

The dominant features of my present design lie in the portions shown in full lines.

The broken lines indicating a lamp socket are omitted from Figs. 2, 3 and 4 for convenience of illustration.

I claim:

The ornamental design for an electric lamp, substantially as shown and described.

DAVID BOROWITZ.
